UNITED STATES PATENT OFFICE

HOWARD E. CHRISFIELD, OF JOHNSON CITY, NEW YORK, ASSIGNOR TO ENDICOTT JOHNSON CORPORATION, OF ENDICOTT, NEW YORK, A CORPORATION OF NEW YORK

DESIGN FOR A SOLE

Application filed September 18, 1929. Serial No. 32,783. Term of patent 7 years.

To all whom it may concern:

Be it known that I, HOWARD E. CHRISFIELD, a citizen of the United States, residing at Johnson City, in the county of Broome and State of New York, have invented a new, original, and ornamental Design for a Sole, of which the following is a specification, reference being had to the accompanying drawing, forming a part thereof.

In the drawing:

Fig. 1 is a plan view of a sole showing my new design.

Fig. 2 is a section on the line 2—2 Fig. 1.

Fig. 3 is an enlarged plan view of a portion of the sole, bounded by the line α , Fig. 1, showing more clearly the raised design.

I claim:

The ornamental design for a sole, substantially as shown.

HOWARD E. CHRISFIELD.
